UNITED STATES PATENT OFFICE.

ERNEST H. WEBB, OF NEW BRUNSWICK, NEW JERSEY, ASSIGNOR TO CHASE COMPANIES, INC., OF WATERBURY, CONNECTICUT, A CORPORATION OF CONNECTICUT.

PACKAGE OF SAFETY PINS, ETC.

Application filed April 11, 1924. Serial No. 705,823.

This invention relates especially to packages of safety pins or similar articles, such as rings, etc., in which the closed or locked safety pins or other articles are inserted into 5 transverse or other slots or apertures in cards, preferably when the card is transversely arched up. Then a breakable cardboard or other retainer strip may be slipped along the back of the card and may preferentially have bottom or edge projections so as 10 to interlock with the inserted pins and securely and positively retain them in position until they are removed for use and thereupon tear or break the retainer strip 15 which is preferably adhesively secured to the card back at a number of places or positively retained in position as by interlocking projections, tongues and apertures formed in the cooperating portions of the 20 strip and card or pins. These safety pin packages which are quite desirable for commercial purposes may be formed in any suitable way as by hand or machine operations along the lines of the applications 25 above referred to, for instance.

In the accompanying drawing showing in a somewhat diagrammatic way illustrative embodiments of this invention:

Fig. 1 is a rear view of an illustrative 30 safety pin card or package,

Fig. 2 is a rear view of another illustrative package.

Fig. 3 is a corresponding transverse section 35 taken substantially along the line 3—3 of Fig. 2.

Fig. 4 is a rear view of another illustrative package, and

Fig. 5 is a corresponding partial section 40 thereof taken along the line 5—5 of Fig. 4.

The safety pins forming these card packages may remain in their closed or locked condition in which they are regularly tumbled and polished and for this purpose the pin card 14 may be formed with one or more 45 series of relatively short pin slots such as 16 which may be transversely arranged when a single row of pins is to be arranged on the card. The pins preferably have their point members inserted through these slots 50 which can be readily done by hand or otherwise, especially if the pin card is then trans-

versely arched up by any suitable means; and when all of these safety pins, rings or other generally similar articles have been inserted into their slots, a cardboard or 55 other retainer strip or member 15 is inserted between the card back and the rearwardly projecting portions of the articles extending through the slots so as to hold them in position during shipment, for instance, the retainer strip being preferably 60 adhesively secured to the card back either throughout their operating faces or at separated points.

As shown in Fig. 1, the retainer strip 15 65 may have rounded or other suitable edge corrugations or locking projections such as 35, extending between adjacent pins to be thereby secured in position, and these edge projections may be advantageously gummed 70 as by any suitable gumming devices which may apply the longitudinally separated edge gummed portions 36 on the two lateral edges of the corrugated retainer strip. These gummed edge projections are of 75 course strongly forced into engagement with the card back, as soon as the card is released from its arched up article inserting position so that it can spring back into flatter position, which forces the pins and 80 interposed retainer strip upward. Other separated or continuous gummed portions may be provided instead of or in addition to these gummed edge projections, such as the central gum spots or portions 37 which 85 may be arranged between each two safety pins or other articles, if desired.

In some cases it is advantageous instead of, or preferably in connection with adhesive methods of securing the tongue and 90 card together, to employ interlocking projections or tongues and apertures formed in the cooperating portions of the retainer strip and card. As shown in Fig. 2, any desired number of apertures 38 may be 95 formed in these parts as by severing them along the crossed or perpendicular dotted lines 37' by means of one or more sharp edged piercing members, and then forcing back against the adjacent rear face of the 100 retainer strip, for instance, the interlocking tongues or projections 39 which are thus

formed. Where this is done by a stamping or die operation under heavy pressure, the adhesive which has preferably been applied between these parts tends to become quickly set as in box staying operations and materially helps to hold the parts together in such positions as are shown in Figs. 2 and 3. If desired, however, a number of apertures such as 38' may be pierced in these cooperating members of heavy paper or light cardboard so as to force the single tongues 39' through this aperture after which they may be advantageously forced or crushed down against the back of the retainer strip, for example, to prevent accidental longitudinal displacement of the retainer strip.

Another illustrative arrangement is shown in Figs. 4 and 5 where the retainer strip 25 is shown as provided with bottom corrugations such as 26 at least on its lateral edge portions so as to have suitable interlocking or holding engagement with the portions of the safety pins or other articles projecting rearwardly through the slots 16 in the card 14. Such holding corrugations or projections may, of course, be stamped up on the retainer strips by any suitable embossing dies which may readily form sufficiently high projections to very materially minimize accidental or undesirable longitudinal movement of the retainer strip under service conditions, even where it is not adhesively secured to the card or otherwise held as by interlocking tongues and apertures in these parts. It is sometimes desirable, however, to provide continuous or separated portions such as 37 of gum or other adhesive on the retainer or card in any suitable positions so as to adhesively hold these parts together in a still more definite and secure way.

This invention has been described in connection with a number of illustrative embodiments, forms, proportions, parts, arrangements, materials and methods of preparation and use, to the details of which disclosure the invention is not of course to be limited, since what is claimed as new and what is desired to be secured by Letters Patent is set forth in the appended claims.

I claim—

1. As a new article of manufacture, a package of safety pins comprising a card formed with a series of spaced and aligned pin-slots shorter than the safety pins to be installed in the card, aligned safety pins installed in the respective slots of the said card, so that a portion of each pin projects from the back of the card, and a breakable, pin-retainer strip inserted between the back of the card and those portions of the aligned pins projecting therethrough, the respective edges of the said pin-retainer strip being formed with notches spaced conformably to the spacing of the slots in the

card for the production of projections upon the edges of the strip for restraining the longitudinal displacement thereof with reference to the card and pins.

2. As a new article of manufacture, a package of safety pins, comprising a card formed with a series of spaced pin-slots shorter than the pins to be installed, safety pins so installed in the said slots that a portion of each pin projects from the back of the card, and a breakable pin-retainer strip inserted between the back of the card and those portions of the pins projecting therethrough, one of the two paper elements having spaced integral conformations corresponding to the spacing of the said slots and interposed between the pins therein to prevent the endwise displacement of the strip with respect to the card and hence the accidental escape of any of the pins.

3. As a new article of manufacture, a package of safety pins, comprising a card formed with a series of spaced pin-slots shorter than the pins to be installed, safety pins so installed in the said slots that a portion of each pin projects from the back of the card, and a breakable pin-retainer strip inserted between the back of the card and those portions of the pins projecting therethrough, the said strip having integral conformations spaced to correspond to the spacing of the slots and co-acting with the pins to prevent its endwise displacement with respect to the card and the accidental escape of any of the pins.

4. As a new article of manufacture, a package of safety pins, comprising a card formed with a series of spaced pin-slots shorter than the safety-pins to be installed, pins so installed in the said slots that a portion of each pin projects from the back of the card, and a breakable pin-retainer strip inserted between the back of the card and those portions of the pins projecting therethrough, one edge of the said strip being formed with notches spaced conformably to the spacing of the slots for the production of projections entering between the installed pins, whereby the two paper elements of the package are held against longitudinal slip-page with the pins individually confined between them, so that any one pin may be removed without releasing any other pin.

5. As a new article of manufacture, a package of safety pins, comprising a card formed with a series of spaced pin-slots shorter than the safety pins to be installed, safety pins installed in the said slots so that a portion of each pin projects from the back of the card, and a breakable pin-retainer strip inserted between the back of the card and those portions of the pins projecting therethrough, one of the two paper elements of the package being provided with integral projections spaced apart conformably with

the spacing of the slots and the separation of the pins for preventing the relative longitudinal slippage of the card and strip, interlocking members formed integral with the card and strip for positively holding them against longitudinal slippage, and an adhesive applied to the card and strip in

spaced relation to the slots and pins, whereby the two paper elements of the package are held against longitudinal slippage with the pins individually confined between them, so that any one pin may be removed without releasing any other pin.

ERNEST H. WEBB.
